PROCESS AND APPARATUS FOR THE COMBINED PNEUMATIC PRELIMINARY DRYING AND PNEUMATIC SUBSEQUENT HEATING OF GOODS

Paul Rosin, Dresden, Germany

Application March 5, 1930, Serial No. 433,346, and
in Germany March 9, 1929

3 Claims. (Cl. 34—34)

It is already well known that pneumatic drying apparatus have a considerably greater efficiency than the ordinary drying apparatus. Where, however, there is a demand for a definite heating of the material that is to be dried, beyond the actual drying of the same, the main advantages of the pneumatic drying apparatus, namely, a smaller capital outlay with greater efficiency and a more satisfactory consumption of heat, are to a greater or less extent lost. The satisfactory utilization of the heat of a single working pneumatic drying apparatus is based on the fact that the extent of the waste-heat losses is determined essentially by the dew point of the waste gases. Since in the case of every pneumatic drying process the exchange of heat can take place in the continuous current, it will be found that where the drying process is followed by a heating treatment at temperatures higher than the final temperature of the drying process, the waste-heat losses in the case of a single working pneumatic drying apparatus are determined mainly by the ultimate temperature of the subsequently heated material; thus, the higher the ultimate temperature of the material, the less economically will an apparatus of this kind work.

By means of the process hereinafter described it becomes possible, even though the material to be dried may have to be subsequently heated, to obtain, with a very cheap and efficient apparatus—such as claimed for example—a very satisfactory consumption of heat from the single pneumatic drying part of the apparatus.

The present invention consists essentially in the combination of a pneumatic drying apparatus and a pneumatic heater (a device for the exchange of heat), wherein these are so combined as to cause the hot gases to give off a portion of their heat content first of all to the material that has already been dried—for the purpose of subsequent heating—and then to give off the remainder of their heat content to the fresh material—for the purpose of preliminary drying. By this means it becomes possible to heat the material and to submit to it a subsequent heating with the same hot gas in one and the same current, whereby, as is the case with the ordinary pneumatic drying apparatus, the waste-heat losses are determinable mainly by the dew point temperature of the hot gas after the drying process has been carried through. The process is suitable for any and all kinds of material which can be treated pneumatically.

An apparatus which works in accordance with the above described combined process is shown

diagrammatically in elevation on the appended drawing to which reference will now be made. The burnt gas passes at the necessary temperature out of the flue *a* into the system of pipes comprising the pipes *b*, *c*, and *d* and thence through the cyclone fan *e* into the piping *f*—*g*. The gas is sucked out of the pipe *g* either directly by means of the exhauster *m* or through a separating device *h* into the cyclone fan *l*. The separating device *h* is included in the gas circulatory system comprising the pipe *g*, the said device, a pipe *i* and a disintegrator *k* which is connected to the pipe *g*. The material to be dried is fed through a suitable device *n* (for example, a screw conveyer) through the lock *o* into the pipe *f*. From here it is carried along by the gas current which separates it in the cyclone fan *l*. The lock *p* allows the pre-heated material to be fed through the pipe *q* into the hot gas current, which, after further heating the material, or if need be after the subsequent drying of the material, deposits it in the pipe system *b*—*d* leading to the cyclone fan *e*. The finished material is discharged through the lock *r* and taken away by means of a suitable attached conveyer device *s*, or other means.

The heating system *b*—*d* is shown in the drawing as a system of pipes telescoped one into the other. Instead of this, however, pipes lying alongside one another and connected by means of quarter bends can also be used. The dimensions of the pipes and of the entire apparatus will naturally depend entirely upon the object and efficiency desired from time to time. Further, the rotary drying apparatus referred to in the drawing can be replaced by a simple system of pipes. The pre-dried material may be, according to its condition and should occasion arise, carried away by means of some other conveyer device, instead of through the inclined pipe *q*. Finally, it may appear appropriate to place the devices *o* and *q* alternately in the falling and rising current of gas, or at some other point.

According to the desired temperatures of the material to be dried, the process can also be established in such a manner that the material to be treated passes through not only two, but also several stages of heating; the quantitative proportions of the hot gas and of the material as also its characteristics can render these measures, *inter alia*, imperative.

By way of an instance of the use to which the present process can be applied, the preliminary drying and preliminary heating of a slow-burning coal may be mentioned. These proc-

esses are normally carried out in the first portion of the sweating oven, so that for the actual sweating itself it is only the remaining portion of the oven that can be used. But the proportion of capital outlay necessary for the drying and preliminary heating processes is in the case of a sweating oven considerably higher than the capital outlay in the case of a plant in accordance with the above described process. As against this, the somewhat greater consumption of heat, which is very much more satisfactory than in other drying processes, is negligible. Thus, the efficiency of an expensive sweating oven can be increased by the separate drying and pre-heating of the coal in a cheap and intensively working apparatus, such as is provided for by the present process, without any considerable consumption of heat.

I claim:

1. Apparatus for drying and subsequently heating materials, comprising in combination means for supplying hot gases, a system of pipes leading therefrom, a cyclone fan connected to said system, a separating device, a pipe connecting said cyclone fan to said separating device, means for feeding said material into said pipe, a disintegrating device, having an inlet

which is connected to said separating device and an outlet which is connected to said pipe connecting said cyclone fan to said separating device, a further cyclone fan, means for connecting the latter to said separating device, an exhauster device connected to said further cyclone fan, and means for connecting the further cyclone fan to said system of pipes at a point in closer proximity to said means for supplying hot gases than said pipe interconnecting said first mentioned cyclone fan to said separating device.

2. Apparatus for drying and subsequently heating materials as claimed in claim 1, wherein said system of pipes comprises a number of telescopically arranged pipes arranged in contra-flow formation.

3. Apparatus for drying and subsequently heating materials as claimed in claim 1, wherein said system of pipes comprises a centrally arranged riser tube connected to said means for supplying hot gases, and wherein the bottom part of said further cyclone fan is connected to said riser tube in close proximity to the part of the latter connected to said means for supplying hot gases.
